PROTECTIVE WINDOW CONSTRUCTION

Clarence D. Ellithorpe, Springfield Gardens, N. Y.,
assignor to Duplex Electric Co., New York, N. Y.,
a corporation of Delaware

Application June 3, 1938, Serial No. 211,514

8 Claims. (Cl. 109—19)

This invention relates to improvements in bullet proof partition structures and more particularly to such a structure as adapted for bank teller's window cages and similar purposes.

In the provision of bullet resisting structures, especially for bank tellers, and others protecting valuables, it is essential to provide not only for undistorted conversation, but also for unobstructed vision, and for free transfer of articles such as coin, pass books, check books, etc. Heretofore, it has been found very difficult to provide a structure having the necessary requirements without some opening through which a possible robber could shoot. The teller was usually unable to fully protect his valuables and was usually restrained from operating an alarm.

The principal object of my invention is to provide an improved partition structure for teller's cages and the like which not only has unobstructed vision and sound channels for undistorted sound, but is also provided with package transfer means by which free movements of articles across the partition can be had without danger to the teller.

A more specific object of the invention is to provide in a bullet resisting partition structure, sound channels which provide a natural amplification without distortion of sound waves, each channel being provided with means to deflect and reverse the path of any possible entering bullets so that the robber will endanger his own life in shooting into the opening rather than endanger the teller's life.

Another object of my invention is to provide an improved deal tray and package passer construction in connection with a bullet resisting teller's window so that small packages may be freely passed under the window and through the deal tray, such deal tray being partially removable for the transfer of larger articles in the package passer and being removable only when the teller's side of the package passer is closed so that at no time can there be a free opening under the teller's window except through the deal tray.

Further objects and advantages of my invention will appear from the following disclosure of a preferred form of embodiment thereof, taken in connection with the attached drawings, illustrative thereof, and in which:

Figure 1 is a partial perspective view of the teller's window and adjacent partition structure;

Figure 2 is a horizontal cross section above the plane of the counter, and taken through the teller's window;

Figure 3 is a part vertical section, lateral to the teller's window and showing the deal tray construction;

Figures 4 and 5 are horizontal sections taken along the line 4—4 of Figure 3, with Figure 5 showing a different position of certain parts; and

Figures 6 and 7 are vertical sections on the lines 6—6 and 7—7 of Figures 4 and 5 respectively.

In accordance with a preferred form of embodiment of my invention, the bullet proof window 10 is the transparent closure to the opening in the teller's cage or similar partition structure. The window is normally mounted above the counter, the customer's side of which is indicated at 11 and the teller's side of which is indicated at 12. The window is preferably mounted as in a steel frame which includes a pair of vertical channels 14 extending substantially along the entire vertical side. This member has glass engaging wall 14a, channel walls 14b and 14c and flange 14d. Another member 15, which may be of angular shape engages both the window and the flange 14d on the channel 14 and can be secured in any position, irrespective of the window thickness. Only one size of window frame member is needed for any thickness of window.

Although the remainder of the partition is not shown, the S-shaped frame members 16 become effectively secured to the partition work so that between adjacent members 16 between windows, there is no difficulty in closing the partition. For this reason, only the structure between adjacent frame members 16 on each side of a window will be considered and in this area, it is necessary to have free and unobstructed vision, clear and undistorted sound transfer, and safe handling of large and small packages. The clear glass panel 10 readily provides for the unobstructed vision and as hereinafter described, particular arrangements are made for the transfer of the sound waves and the passing of packages, etc., without danger to the teller.

Referring particularly to Figure 2, it will be noted that the window is set back a substantial distance from the edges of the counters so that in normal position, a person speaking will necessarily be away from the glass. It will also be noted in Figures 1 and 2, that the partition members 16 are spaced away from the edges of the window frame 14.

These partition members 16 include face portions 16a, inwardly projecting portions 16b, angular sound channel sections 16c, and they merge

to a pocket formed by walls 16d, 16e and 16f. The corner formed by the walls 16d and 16e is preferably reenforced as by angle 17 and by rod 18. A similar rod 18 may also reenforce the corner formed by walls 16a and 16b as well as the tip of the angle formed by the walls 14b and 14c in the window frame member 14.

The walls 14b and 16c are preferably parallel and form a voice channel 20. This channel is offset and at an angle to the window 10 and it opens into a chamber 21. The channel 22 composed of parallel walls 14d and 16f, leads to the teller's side of the partition from this latter chamber.

15 The chamber 21 which is formed by the partition member walls is in a direct line with the customer's face and in line with a gun which a robber might shoot. It is also in front of the teller but the line is not direct, nor curved. 20 This is due to the fact that the wall 16f on the partition member is in line with the tip formed by the walls 14b and 14c on the window frame member. The result is that conversation will be clear and undistorted. In fact, there is an amplification afforded by the channels and as they are in a natural location for sound waves to pass from the mouth of one to the ears of another person, there is complete freedom of sound passage without conscious knowledge of a solid 25 panel between the persons.

30 There can be no bullet pass through the sound channel, however, because the course of a bullet in channel 20 will be into the pocket formed by the walls 16d, 16e and 16f of the partition member. This not only becomes a trap for directly fired bullets, but all others will ricochet out through the channel 20 toward the firing point. The increased danger to a robber will serve either as a deterrent to his shooting, or will cause a 35 probable self-injury. In no event can any bullets pass entirely through the voice channel into the teller's compartment. In this respect, the structure is not only far superior in freedom of communication, which is its primary function, but it is also far safer in case of possible attempted hold-up due to the returning of the bullet from whence it came.

35 The use of the vertical rods 18 is to be particularly noted. The round steel rods have an unusual resistance to damage far in excess of the strength expected of their size, due to the difficulty of striking them head on as is the case with flat plate. In my construction, they also serve another function, viz., that of holding all 40 of the structure together and may be provided with screw ends or other means (not shown). They greatly facilitate rapid assembly of the entire structure and provide the necessary strength where needed most.

45 The passage of articles, including coins, small pass books, etc., is normally accomplished in the deal tray 30 which is supported on suitable rollers 31, carried by the track 32, such deal tray normally being in the position shown in Figure 3. It will be noted that the window 10 is of a fixed type, being supported at the bottom by a channel or other structural device 33, and the package or coin transfer is thus through the deal tray underneath the glass panel.

50 The pan 34 of the deal tray is inclined downwardly and rearwardly so that any coin or other article inserted in the opening 35 on the customer's side of the window 10, will normally fall to a low point 34a on the teller's side of the window. This makes it particularly easy for

the teller to remove the articles without exposing himself to injury and without any possibility of the teller missing any due to unlighted parts of the tray. Coins or other articles inserted in the deal tray 30 by the teller can be readily removed by the customer.

55 It will be noted that the pan 34 is sharply curved upward in the region 34b on the teller's side of the window so that any tendency of the possible robber to shoot under the window will result in a harmless deflection of the bullet vertically upward. Regardless of the angle used in shooting from the customer's side of the window, there is no tendency of the bullet to come outward and rearward on the teller's side of the cage 20 so that there is no possibility of the teller being injured. The teller can shoot into the deal tray with great effect, however, and no gun port is necessary. The slope of the forward wall facilitates this purpose.

60 It is to be noted that the obliquity of contact of any bullet fired into the deal tray causes it to expend a large part of its effort in deflection so that as great strength is available in my structure as would be had in other structures twice as thick subjected to direct fire. This improved feature also exists in the voice channel, all parts of which are oblique to a shot aimed at the teller.

65 When packages must be passed under the window 10 which are larger than can be accommodated in the deal tray 30, the deal tray may be withdrawn to open up the relatively deep receptacle 40. This is also of a bullet proof nature and is normally closed against access to the customer by the deal tray. On the teller's side, this receptacle is closed against access by the hinged cover 41 which as shown in Figure 2, is conveniently hinged at 43. If the deal tray is in the position shown in Figure 3, the cover can be 70 lifted up to expose the depth of the receptacle.

75 The deal tray may be drawn toward the teller for the purpose of exposing the opening in the receptacle 40 on the customer's side and for this purpose a withdrawal hook 44 is provided. So that this deal tray may not be withdrawn except when the cover 41 is closed, I provide a cam construction shown in Figure 4 and indicated at 80 45 which overlies the hook arm 46 interconnected with the deal tray. As shown in Figure 3, the hook arm 46 is provided with an offset stop portion 47 which engages on the vertical frame work 48 so that the deal tray may not be withdrawn unless the hook portion 44 is elevated. The hook portion 44 cannot be elevated, however, unless the cam 45 is withdrawn and this cannot be accomplished except by turning the knob 49 in a counter-clockwise direction. The knob 49 is provided with cam engaging member 50 which operates in a suitable slot 51 within the cam 45, and when the knob is turned in the counter-clockwise direction it will turn the cam 45 in a counter-clockwise direction against the action of spring 52 which normally holds the cam 45 in a locked position.

85 The knob 49 projects through the framework 53 constituting a part of the counter which is provided with a slotted portion in keyed relation with the part 50 when in the position shown in Figure 4. The result is that when the knob 70 is turned to the position shown in Figure 5 to release the cam 45 from the arm 46, the projecting member 50 cannot be raised up through the framework 53 and the cover cannot be raised. A suitable spring 55 is provided to nor- 90

5 mally turn the knob 49 in a clockwise direction, to force the cam 45 into the position shown in Figure 4 and in such position, the deal tray may not be moved.

10 5 If the customer desires to pass large articles to the teller, the teller will rotate the knob 49 to the counter-clockwise position, after which he can raise the hook 44 and pull the deal tray toward him. The deal tray is pulled to a position in which the shoulder 34c engages the channel 33 and seals the passage between the customer's side of the window and the teller's side of the window. The desired opening on the customer's side of the window is thus provided 15 for the insertion of the package in the receptacle.

20 10 After the articles have been placed within the receptacle 40, the teller may remove them by pushing the deal tray to the position shown in Figure 3, during which the cover 41 may not be opened. As soon as the tray is in the position as shown in Figure 3, the retractile spring 52 will tend to force the cam 45 into the locking position shown in Figure 4 and the retractile spring 55 will turn the knob 49 so that the key 25 15 member 50 may be withdrawn through the suitable keyhole opening in the frame 53 so that the cover can be raised. At no time, however, can there be an opening into the receptacle 40 from the both sides of the partition work.

30 20 It will thus be seen that I have provided for the essential requirements of safety, clear vision and sound, and substantially fool-proof construction. The structure is readily assembled in standard sizes with minimum of costly fittings and with the least objectionable external 35 25 or internal appearance. It is adaptable to any form of partition for tellers or others and may be installed independently or in conjunction with other cages.

40 30 While I have shown a preferred form of embodiment of my invention, I am aware that other modifications can be made thereto, and I therefore desire a broad interpretation of my invention within the scope and spirit of the disclosure herein and of the claims appended hereinafter.

45 I claim:

50 40 1. In combination with a bullet resisting panel structure of the class described, a deal tray movably mounted thereunder, and a package receiver under said deal tray, and substantially covered thereby, a cover to complete the covering of said package receiver, means on one side of the panel structure to move said deal tray, 55 45 means to automatically lock said moving means against movement and means to hold said locking means against unlocking unless the deal tray cover is in a position normally closing the package receiver.

60 50 2. In combination with a panel structure, means to pass articles below said structure without possibility of harm from the outer side which comprises a deal tray normally positioned under the panel and open on both sides thereof, and a package receiver below said deal tray, said deal tray substantially closing the opening in said package receiver, a cover cooperating with the deal tray and closing the remainder of the package receiver opening, means operable from only 65 60 one side of said panel to slide said deal tray under said cover to expose said package receiver on the outside, and means to open said cover when said package receiver is unexposed on the outer side, to expose the package receiver on the inner side.

70 65 3. In combination with a panel structure, means to pass articles below said structure without possibility of harm from the outer side which comprises a deal tray normally positioned under the panel and open on both sides, said deal tray 75 70 having a sharply inclined bottom wall on the inner side of the panel to deflect bullets upward therefrom, and a package receiver below said deal tray, said deal tray substantially closing the opening in said package receiver, a cover 80 75 cooperating with the deal tray and closing the remainder of the package receiver opening, means to slide said deal tray under said cover to expose said package receiver on the outside and means to open said cover when said package receiver is unexposed on the outer side, to expose the package receiver on the inner side, said opening means including a safety latch, said latch normally engaging said deal tray slide means to prevent movement of the deal tray 85 80 when the cover is being opened or is open.

90 85 4. A receptacle having a bottom, side walls and end walls, and a closure containing two adjacent movable sections for completely closing the top of the receptacle, means mounting one of said sections for sliding movement beneath the other to open the receptacle adjacent one end thereof, means mounting the other of said sections for movement relative to said one section to open the receptacle adjacent the other 95 90 end thereof and locking means operative to prevent movement of either of said sections to open position when the other section is open.

100 95 5. A receptacle having a bottom, side walls and end walls, and a closure including two adjacent movable sections for completely closing the top of the receptacle, means mounting one of said sections for sliding movement beneath the other to open the receptacle adjacent one end thereof, means mounting the other of said sections for movement relative to said one section to open the receptacle adjacent the other end thereof, means for moving each section to open position, latching means individual to each of last recited means for locking each section in closed position and means operative when either of said latching means is released to actuate the other of said latching means whereby to prevent either section from being opened when the other is unlocked.

105 100 6. A receptacle having a bottom, side walls and end walls, and a closure comprising two adjacent movable sections for completely closing the top of the receptacle, means mounting one of said sections for sliding movement beneath the other to open the receptacle adjacent one end thereof, means mounting the other of said sections for swinging movement about a fixed axis to open the receptacle adjacent the other end thereof, an arm extending under said latter section and connected to said slidably movable section whereby said slidable section may be drawn under the other section, latching means on said arm for engagement with a wall of said receptacle for locking said slidable section in closed position, a handle on said other section for opening said section, said handle being provided with latching means to lock said section in closed position and means operative when either of said latching means is released to actuate the other of said latching means whereby to prevent either section from being opened when the other is unlocked.

110 110 7. In combination with a panel structure, means to pass articles below such structure with-

- out possibility of harm from the outer side which comprises a stationary package receiver positioned under said panel and extending on either side thereof, a closure including two adjacent 5 movable sections for completely closing the top of said package receiver, means mounting one of said sections for sliding movement beneath the other to expose said package receiver on the outer side, and means to open the other of said 10 closure sections when said package receiver is unexposed on the outer side to expose the package receiver on the inner side, said opening means including a safety latch, said latch normally engaging said closure slide means to prevent movement of the slidable section when the other closure section is being opened or is open.

8. In combination with a panel structure, means to pass articles below said structure without possibility of harm from the outer side, which comprises a stationary package receiver positioned under said panel and extending on either side thereof, a closure including two adjacent movable sections for completely closing the top of said package receiver, means operable from only one side of said panel to slide the outer closure section under the inner closure section 10 to expose said package receiver on the outer side, and means to open said inner closure section when said package receiver is unexposed on the outer side to expose the package receiver on the inner side. 15

CLARENCE D. ELLITHORPE.
